PEDESTAL

Calvin S. Greenwood and Lewis C. Travers, Gardner, Mass., assignors to P. Derby Company, Gardner, Mass., a corporation of Massachusetts

Application April 30, 1932, Serial No. 608,452

6 Claims. (Cl. 155—3)

This invention relates to a pedestal or pedestal unit for a chair or desk but particularly designed to support both a chair and a desk for school purposes and the like.

The principal objects of this invention are to provide a pedestal in a single piece having means for supporting the seat of a chair in front and a desk top in back, said supporting means being of such shape as to permit the screws to be driven into the chair seat at the points at which the wood in the seat is the thickest and of such shape as to prevent a tendency to rock about any one point, thus permitting of a durable fastening of the seat or desk to the pedestal; and to provide a construction in which the elevation of the chair or seat can be changed in a very simple manner to suit it for pupils of different ages and yet provide just as firm a fastening as if the means for raising the chair or desk were not employed.

Other objects and advantages of the invention will appear hereinafter.

Reference is to be had to the accompanying drawing, in which

Fig. 1 is a perspective view of a combined chair and desk pedestal for school purposes constructed in accordance with this invention;

Fig. 2 is a perspective view of the pedestal with two triangles for adjustment purposes shown just above the rests;

Fig. 3 is a plan of one of these triangles, and

Fig. 4 is a sectional view centrally through the chair holding section.

This invention, as stated, is particularly useful when applied to school furniture. Ordinarily the pedestal 10 to which the invention is applied is provided with a rear branch 11 and with a front branch 12, one supporting a desk top 13 and the other a chair seat 14. This pedestal is provided with an elliptical base 15 to give it a firm non-rocking support. Of course, in the front and back rows in a school, the pedestal may be made to support a desk in the front row and a chair only in the rear row and have only one branch.

The branches 11 and 12 are provided with rests 16. Instead of being made circular or square as usual, they are made of a general triangular shape, the triangles having curved sides preferably. This shape is provided so that, when bolts or screws are put through the corners into the bottom of the chair or desk, they will come at the parts of the chair seat where the wood is of full thickness and not the parts where the wood is saddled out. In this way a firmer attachment of the chair seat can be secured and one that will be

more durable and less likely to split the seat after severe usage.

As ordinarily manufactured pedestals for this purpose have to be made in several sizes at the factory for the accommodation of pupils of different ages. In accordance with this invention, the cast iron pedestals 10 are made at the factory in a smaller number of sizes. This somewhat reduces the expense and reduces the amount of storage room required because only one set of pedestals has to be stored ready for sale.

The pedestal, as actually made, is constructed of a size suitable for the shortest pupil and, when it is desired to change them for the use of taller or older pupils, the change is made by introducing a ring or triangle 20. These are generally of the same shape as the rest 16 and are made of cast iron with shelves 23 having notches 21 in the three angles. These adjusting pieces are made of different widths or heights. A set of them is used having different heights for the purpose of adjusting the seat and desk to whatever height may be desired. These triangles, made of cast iron preferably, are placed on the rests 16, one of the desired height being selected, and then bolts or screws 22 are introduced through them and through the rest and into the bottom of the chair or desk to secure the parts firmly in position. The adjusting pieces 20 are slightly rabbeted at 23 at their corners or, in other words, the shelves on the lower side at the three corners of the adjusting pieces are set inwardly so as to form a rabbet at this point and allow the edge of the adjusting piece to project over the rest 16 as shown in Fig. 4. This furnishes a means for locating them in the proper position quickly and accurately for the application of the bolts.

It will be seen that on account of the particular location of these notches 21, the parts of the chair seat which are saddled or depressed are not used for the screws with which the chair seat is secured but the screws pass into the thickest parts of the wooden seat.

Although we have illustrated and described only one form of the invention we are aware of the fact that modifications can be made therein by any person skilled in the art without departing from the scope of the invention as expressed in the claims. Therefore we do not wish to be limited in this respect but what we do claim is:—

1. A piece of furniture comprising a cast metal pedestal having a flat top rest, a detachable and replaceable adjusting piece located on said rest and a chair or desk bottom secured to the rest

- through said adjusting piece, whereby said adjusting piece can be replaced by another of different thickness to adjust the elevation of the chair or desk.
5. As an article of manufacture, a pedestal for a combined chair and desk, said pedestal consisting of a cast iron base having branches extending forwardly and rearwardly, a triangular horizontal rest at the top of each branch integral with the casting, the broad bases of the two rests being located inwardly, adjusting pieces consisting of cast iron of the same shape as said rests having notches at their corners and located on the two rests, a chair seat secured to one of said rests through the adjusting piece, and a desk top secured to the other rest through the adjusting piece, said notches receiving the fastening means for the chair and desk. 5
6. As an article of manufacture, a pedestal for a combined chair and desk, said pedestal consisting of a cast iron base having branches extending forwardly and rearwardly, a horizontal rest at the top of each branch integral with the casting, adjusting pieces of the same shape as said rests having notches at their corners and located on the two rests, a chair seat secured to one of said rests through the adjusting piece, and a desk top secured to the other rest through the adjusting piece, said notches receiving the fastening means for the chair and desk. 10
2. A piece of furniture comprising a cast metal pedestal having a flat top rest, a detachable and replaceable adjusting piece located on said rest, and a chair or desk bottom secured to the rest through said adjusting piece, said adjusting piece having notches for the reception of the bolts or screws.
3. A pedestal for furniture comprising a flat top rest of general triangular form and a removable adjusting piece of similar form located on the top of the rest, the chair or desk bottom being secured to the rest through the adjusting piece at the corners thereof.
4. As an article of manufacture, a pedestal for a combined chair and desk, said pedestal consisting of a cast iron base having branches extending forwardly and rearwardly, a triangular horizontal rest at the top of each branch, adjusting pieces located on the two rests, a chair seat secured to one of said rests through the adjusting piece, and a desk top secured to the other rest through the adjusting piece, and fastening means passing through said adjusting pieces for the chair and desk. 20
